UNITED STATES PATENT OFFICE.

ROBERT EDWIN REARDON, OF CHERRYDALE, VIRGINIA.

DUMMY CARTRIDGE.

1,347,659.

Specification of Letters Patent.

Patented July 27, 1920.

Application filed March 13, 1917, Serial No. 154,564. Renewed January 2, 1920. Serial No. 349,092.

To all whom it may concern:

Be it known that I, ROBERT EDWIN REARDON, a subject of the King of Great Britain, and a resident of Cherrydale, Virginia, have 5 invented certain new and useful Improvements in Dummy Cartridges, of which the following is a full description.

This invention relates to improvements in dummy cartridges for practice rod attachments, and the objects of the invention are 10 to provide a simple and effective form of dummy cartridge for magazine practice with practice rods.

Further objects are to minimize complete 15 compression of the retracted strain, and to so construct the cartridges that they may be manufactured at small cost, and consists essentially of the improved construction hereinafter described in detail and illustrated in the accompanying drawings forming 20 part of the same.

In the drawings,

Figure 1 is a longitudinal section through 25 a cartridge embodying the present invention. Fig. 2 is a cross sectional view.

Referring to the drawings, A represents an outer shell comprising a nose 11 shaped to correspond with a bullet of a cartridge and a body portion 12 shaped to correspond 30 with the body portion of a cartridge, the shell A, however, is all pressed from a single piece of metal such as sheet metal, and is screw threaded interiorly at 13 to receive a correspondingly threaded end cap 35 or plug 14.

15 represents the striking rod extending longitudinally in the shell A and adapted to be projected through the bore 16 in the nose 11. The end of the striking pin opposite to that which projects through the nose has a pin 17 which extends through a perforation or orifice 18 in the cap 14.

The rod is held in normal position and retracted after it has been projected 40 forwardly by means of a spiral compression spring 19 which abuts a shoulder 20 at the inner side of the pin 17, and a collar 21 supported by a sleeve 22 which fits a cylin-

drical recess 23 in the nose 11 and is securely held therein. 50

Complete compression of the spring 19 is prevented by means of arms or wings 24 adapted to abut the collar 21 before the spring 19 is completely compressed.

The invention is adapted to be used in 55 conjunction with a target practice rod, which term designates a spring retracted rod adapted to be projected from the barrel of a fire arm or the like by means of the hammer or bolt mechanism. 60

In using the dummy cartridges which form the present invention, the rod 15 in Figs. 1 and 2 is adapted to be struck by the hammer or by the spring actuated bolt and thereby projected forwardly to strike 65 the target practice rod and propel the same.

It will be seen that by constructing the shell or casing all in one piece, the cost of manufacturing is reduced, and at the same time, a stronger article is produced. When 70 an ordinary unfilled cartridge shell is used, the bullet portion is liable to become detached from the shell proper and this defect the present invention overcomes.

As many changes could be made in the 75 above description and many apparently widely different embodiments of my invention within the scope of the claim constructed without departing from the spirit or scope thereof, it is intended that all matter contained in the accompanying specification and drawings shall be interpreted as illustrative and not in a limited sense. 80

What I claim as my invention is:

A dummy cartridge for target practice 85 rods comprising a casing shaped like a cartridge, an end cap, a longitudinally extending rod, a pin on the rod extending through the cap, a tube surrounding the rod on the interior of the casing, a collar carried by the tube, a spring extending between the collar and the pin on the rod and adapted to retract the rod. 90

In witness whereof I have hereunto set my hand.

ROBERT EDWIN REARDON.
